CLAIM

The ornamental design for a rack, as shown and described.

DESCRIPTION

FIG. 1 is a top, right, front perspective view of a rack showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken line showing is for the purpose of illustrating unclaimed portions of the rack and forms no part of the claimed design.

1 Claim, 4 Drawing Sheets
